UNITED STATES PATENT OFFICE.

ABRAHAM A. NEWMAN, OF CHICAGO, ILLINOIS.

TIMEKEEPER.

No. 805,376.

Specification of Letters Patent.

Patented Nov. 21, 1905.

Application filed September 9, 1904. Serial No. 223,809.

To all whom it may concern:

Be it known that I, ABRAHAM A. NEWMAN, a citizen of the United States of America, residing at Chicago, in the county of Cook and State of Illinois, have invented certain new and useful Improvements in Timekeepers, of which the following is a specification.

My invention relates to certain new and useful improvements in timekeepers; and its object is to produce a device to coöperate with the type of timekeeper illustrated in my application filed on even date herewith and allotted Serial No. 223,808.

The particular object of my invention will appear more fully and at large in the course of this specification, and the invention is fully illustrated in the accompanying drawings, in which—

Figure 1 is a sectional view showing certain parts of the timekeeper in elevation and other parts in central longitudinal section in the line 1 1 of Fig. 2. Fig. 2 is a horizontal section in the line 2 2 of Fig. 1. Fig. 3 is a similar view showing the parts in the different positions, and Fig. 4 is a perspective view of one of the adjustable tripping-posts of the device.

Referring to the drawings, A is the cabinet which contains the timekeeper and operating mechanism, the same consisting of a time mechanism *a*, centrally disposed within the cabinet, and a hopper *a'* on the upper end of the clock-arbor, said hopper opening into a flat radial tube *a''*, adapted to guide a check from the hopper into a pocket. No further description of the time-keeping mechanism proper will be necessary at this time, as the same is fully set forth in the application above referred to.

The cover A' of the cabinet is perforated at its center above the hopper *a'*, and a block B, having a coin-slot, is inserted in the perforation. This block has an outwardly-turned flange *b*, which serves to support the mechanism of my present improvement. To the flange *b* is journaled a circular plate C, which is provided with a plurality of sector-shaped openings *c*, alternating with similar solid portions, the openings and solid portions being of equal angular extent. The plate C is eccentrically disposed with reference to the arbor of the clock and the hopper *a'*. The plate C carries at the center of its lower face a star-wheel C', having points *c'*, corresponding in number to the spaces on the plate C. In the

form of device herein illustrated a plate is shown with three perforate sectors and three solid sectors, and the star-wheel is consequently shown with six points; but it is evident that the number of spaces can be varied, if desired.

A bracket *d* is secured to the flange *b*, the said bracket carrying a spring D, which bears at its end a roller *d'*, bearing against the star-wheel C'. The spring D is made of sufficient tension to cause the plate C to remain in one of the six possible angular positions wherein the roller *d'* lies at the bottom of the notch between two adjacent points on the star-wheel. In any of these positions the plate will occupy a position so that the slot in the block B lies close to the left-hand edge (when looking down) of one of the spaces on the plate C.

The hopper *a'* carries at its upper edge a cylindrical flange A³, upon which are secured a plurality of movable blocks E, having set-screws *e*, by which they can be locked in place, and bearing upwardly and outwardly extending posts *e'*, adapted to engage with the points of the star-wheel. The hopper is provided with a dial A², divided into hours and minutes, and each of the blocks E is provided with a pointer, the end of which is close to the dial and by the aid of which the tripping-post can be set in any desired position.

The operation of my improved device will be readily apparent from the foregoing description. In practice the hopper *a'* and tube *a''* rotate in the direction of the arrow in Fig. 2, and when the parts are in the position illustrated one of the open spaces in the plate C is below the slot in the cabinet, so that the checks used in the timekeeper can be dropped through into the hopper. As the hopper moves on from the position illustrated in Fig. 2 one of the tripping-posts engages with one of the points on the star-wheel, moving it from the position indicated in Fig. 2 to that indicated in Fig. 3. The slot, it will be seen, is open during all this time. The roller *d'* on the spring D eventually rides up over one of the points on the star-wheel and immediately runs down on the opposite side thereof, swinging the plate C until the slot lies immediately over the left-hand edge of the solid space next adjacent to the open one over which it was last situated. This closes the slot in the cabinet and makes it impossible for a workman to insert his

check. The slot remains closed in this way until the next succeeding tripping-post strikes the next point on the star-wheel, when the operation is repeated and the slot is opened. 5 The figures on the dial A² are so arranged that the pointer on the block E lies opposite the figure indicating the exact moment when the roller runs over the point of the star-wheel and completes the movement of the 10 plate C.

In practice the tripping-posts are set in such a way that the slot will be closed a short time after the workmen are all supposed to have arrived and will open a short time before they 15 should begin to leave. In many factories it is desired to have an accurate record of the number of minutes each workman was absent, and this is kept by the other mechanism of the timekeeper. In case, however, a work- 20 man is unusually late—say one-half hour or an hour—it is often desirable that he be compelled to explain his tardiness immediately to the foreman or other person in charge. My present invention makes this possible, for if 25 a workman comes in after the slot of the cabinet is closed it is impossible for him to insert his check in the machine and he must take it in person to the foreman, giving an explanation of his absence, if required. Otherwise 30 his check would have to be left on the rack and he would get no credit for any attendance on that day or half-day.

I realize that considerable variation is possible in the details of this construction without departing from the spirit of the invention, 35 and I therefore do not intend to limit myself to the specific form herein shown and described.

I claim as new and desire to secure by Letters Patent—

1. In a device of the class described, the combination with a series of check-receiving pockets, of a slot through which the checks are passed, clock-controlled mechanism for determining which of the series of pockets the 45

checks enter and means for periodically closing said slot.

2. In a device of the class described, the combination with a cabinet slotted to receive checks, a time mechanism, and a dial carried by the time mechanism, of tripping-posts adjustably secured to the dial, a plate journaled adjacent to the slot and having perforations adapted to periodically register with the same and a star-wheel on the plate arranged to be 55 engaged by the tripping-posts.

3. In a device of the class described, the combination with a timekeeper mechanism having a series of pockets to receive checks, clock-controlled guiding means for directing checks 60 to said pockets successively and a slot to introduce said checks to the guiding mechanism, of a clock-controlled device for periodically closing said slot.

4. In a device of the class described, the combination with a timekeeper mechanism having a series of pockets to receive checks, clock-controlled guiding means for directing checks to said pockets successively and a slot to introduce said checks to the guiding mechanism, 70 of means under the control of the guiding means for periodically closing said slot.

5. In a device of the class described, the combination with a timekeeper mechanism having a series of pockets to receive checks, clock-controlled guiding means for directing checks to said pockets successively and a slot to introduce said checks to the guiding mechanism, 75 of a perforated plate journaled adjacent to said slot and engaging devices carried by the guiding means for rotating said plate to periodically open and close slot.

In witness whereof I have signed the above application for Letters Patent, at Chicago, in the county of Cook and State of Illinois, this 85 2d day of September, A. D. 1904.

ABRAHAM A. NEWMAN.
